UNITED STATES PATENT OFFICE.

JEFFERSON D. THOMPSON, OF NEW YORK, N. Y.

SKYLIGHT CONSTRUCTION.

974,310.

Specification of Letters Patent. Patented Nov. 1, 1910.

Application filed May 27, 1909. Serial No. 498,631.

To all whom it may concern:

Be it known that I, JEFFERSON D. THOMPSON, a citizen of the United States, residing at New York, in the county of New York and State of New York, have invented new and useful Improvements in Skylight Constructions, of which the following is a specification.

My present invention relates to certain new and useful improvements in skylight constructions and has for one of its principal objects the provision of a novel form of cushion or glazing strip designed to constitute the sole supporting means for the glass plates of the skylight, said strip comprising a plurality of relatively thin, upstanding spaced or separated walls of soft metal, upon the upper longitudinal edges of which the glass plates rest, the construction and material of the cushion or glazing strip being such that a close, water and air tight joint will necessarily result between, or at the points of contact between, the strip and the glass plates resting thereon, and this notwithstanding the usual irregularities, unevenness, and like defects characteristic of glass plates employed in skylight constructions.

A further object of the invention is to provide a novel form and construction of skylight bar astragal with which my improved cushion or glazing strip is coöperatively associated.

A still further object of the invention is the provision of a novel manner of and means for attaching in position the caps or crown pieces, whereby to provide a watertight connection between the parts, and to permit the caps or crown-pieces to be applied with ease and facility without being compelled to first measure off and punch the bolt-securing holes through which pass the bolts that secure the caps or crown-pieces in position.

Further objects of the invention will hereinafter appear from a reading of the detailed description now to follow.

The invention comprises the features of construction and arrangement of parts as typified in the embodiments illustrated in the accompanying drawings, wherein—

Figure 1, is a vertical cross-sectional view of a portion of a skylight construction made in accordance with my invention. Fig. 2 is a longitudinal section taken on the line *a—a* of Fig. 1. Fig. 3 is a perspective view of

one form of cushion or glazing strip made in accordance with the invention. Fig. 4 is an end elevation of an improved form of curb-clip. Fig. 5 is a vertical cross-sectional view showing in use a slightly different form of cushion or glazing strip. Fig. 6 is a perspective view of the cushion or glazing strip shown in Fig. 5. Fig. 7 is a vertical cross sectional view illustrating a novel construction of astragal or skylight bar formed of sheet metal. Fig. 8 is a longitudinal section taken on the line *b—b* of Fig. 7.

Referring to the drawings Fig. 1, the reference letter A, designates generally one form of astragal or skylight bar which in the instance shown is made from one integral piece of rolled or cast metal, and comprises the central vertical web 10, having at its base on opposite sides the two integrally formed outstanding wings or flanges 12, the free ends 13, of which are directed upward as shown to provide the lower pair of gutters 14. The central web 10, is further provided upon opposite sides, at points directly above the wings or flanges 12 with outwardly and upwardly extending, integrally formed, glass-plate supporting flanges 15, upon the free longitudinal edges of which are attached my improved soft-metal cushions or glazing strips S presently to be described. The central web 10, extends above the plane of the glass-plate supporting flanges 15, and the cushions or glazing-strips 90 resting thereon, as clearly shown in Fig. 1, the said flanges 15, providing gutters 16, to drain away any water that may accidentally find its way between the joints through faulty construction due to carelessness on the part of the builder. At suitable predetermined points, the upper longitudinal edge of the web 10, is provided with circular openings 17, cut entirely through the thickness of the web, each opening being intersected by a slot 18, leading therefrom to the edge of the web as more clearly shown in Fig. 2. Within each opening 17, is located the head 19 of an eye-bolt, the shank 20, of the bolt projecting vertically through the said slot 18, and the bolt being maintained in true vertical alinement with the web 10, and against lateral displacement by means of washers 21, of greater diameter than the circular openings 17, one washer 110 being located on each side of the web, and through which washers and the eye of the

2
bolt is passed a tubular, or other form of rivet 22, the swaged end of which securely maintains the parts in position with the shank of the bolt in true vertical alinement 5 with the web. The eye-bolts have pointed ends 23, for a purpose presently to be explained.

The reference numeral 24, designates the cap or crown-piece which may be made of sheet copper or other metal, the free lower edges of which are shown as provided with reentrant bends 25, between the walls of which are located the thin soft metal strips 26, preferably of lead, the free or unclamped 15 portions of which are pressed in close facial contact with the upper face of the glass-plates 27, of the skylight to provide a watertight seam or joint between said strips and the glass-plates upon which they are in contact. In applying and securing the cap or crown-piece in position, according to my improved method and construction, the horizontal portion 28, thereof is first centered upon the pointed ends 23 of the eye-bolts 20 and by downward pressure applied thereto, the said pointed ends are forced therethrough, causing upstanding burs 29, to be formed around the pierced openings thus formed, which burs closely hug or embrace 25 the shanks of the eye-bolts to form a close joint therewith. The cap or crown-piece is forced down bodily until the soft metal strips 26, carried thereby, are in a position 30 to be pressed into contact with the glass plates 27, and nuts 30, are then screwed upon the threaded shanks of the bolts, the said nuts being provided on their under face with a cavity 31, up into which the burs 29, project, the marginal edges of the nuts contacting with the horizontal portion 28, of 35 the cap or crown as shown to provide a close joint that will effectually exclude moisture.

The reference letter C, designates my improved curb-clip, the purpose of which is to 40 prevent endwise movement of the glass-plates and to lend rigidity to the whole structure generally. The curb-clip as shown in Figs. 2 and 4, comprises a plate 32, having a general outline corresponding to the 45 cross-sectional shape of the cap or crown and a portion of the skylight bar, so as to fit into the cap and thereby allow cap to pass over said clip and shed the water freely and not cause it to back up and freeze in freezing 50 weather. Formed integral with and extending rearwardly from the rear face of the plate 32, are a pair of spaced parallel ears 55 33, adapted to embrace the opposite sides of the web 10, of the skylight-bar at the end 60 thereof, the said clip being secured in position by means of a bolt or hollow rivet 34, passed through apertures formed in the ears and web respectively as more clearly shown in Fig. 2.

65 My improved cushion or glazing strip,

which forms an important feature of this invention, is designed primarily to provide a somewhat yielding, yet amply rigid support for the heavy glass plates of the skylight and one wherein a close and continuous or unbroken contact may be had between the strip and the surface of the glass plate resting thereon, notwithstanding the surface irregularities, imperfections or undulations usually found in glass plates employed in skylight constructions, even though said glass plates be of the so-called "ribbed" or "corrugated" type. In the form illustrated in Fig. 3, the cushion or glazing strip is of substantially H-shape. In the cross-section, and comprises the relatively thin, spaced parallel walls 35, the free longitudinal edges 36 of which are preferably, although not necessarily, somewhat thinner than the walls proper, said walls being joined by a transverse web 37, which may be arranged centrally or otherwise. The strip is composed of some suitable soft metal, such as lead, and owing to the fact that the walls thereof are relatively thin, it will be apparent that the heavy glass-plates resting thereon will bear upon these thin walls with considerable pressure, causing any irregularities, ribs or uneven portions in the plates to sink into the thin upper edge of the walls and thus make close contact between these parts with the result that a water and air tight joint will be formed. Furthermore the strips being formed of soft metal a somewhat yielding support for the glass plates is provided, thus liability of breakage is greatly reduced. A further advantage resulting from my improved construction of cushion or glazing strip wherein a plurality of relatively thin glass-plate supporting walls is provided, resides in the fact that an air space 38, is formed between the walls which will effectually intercept the flow of any water along the under surface of the glass plates in case water should, by reason of imperfect construction, pass between one of the walls and the surface of the plate resting thereon.

The form of cushion or glazing strip illustrated in Figs. 1 and 3, is reversible as will be apparent. In placing the same in position upon the flange 15, of the skylight bar, one of the channeled portions thereof is caused to straddle the upper edge of the flange and the flange embracing portions are then pressed or hammered into close contact with the flange to hold the strip in position. Obviously the cushion or glazing strip may be readily and quickly applied and removed for repair if desired.

In Figs. 5 and 6, I have illustrated a slightly different form of cushion or glazing strip made according to my invention. In the instance shown the soft metal strip S', is in channel form and comprises the thin,

parallel spaced walls 35', the upper longitudinal edges 36', of which are reduced in thickness and the said walls being joined at the base by the transverse web 37'. The 5 strip is soldered to the sheet metal skylight bar 40, which bar has an upstanding central portion 41, over which a sheet metal cap or crown 42 is placed, the free edges 43, of the cap or crown bearing upon the upper surface of the glass plates 27'.

In Figs. 7 and 8, I have shown my improved cushion or glazing strip S, associated with a novel form and construction of skylight bar formed from sheet metal, said bar 15 having all the structural characteristics of the bar illustrated in Figs. 1 and 2, but being cheaper and simpler to manufacture in view of the fact that it is formed entirely from sheet metal. As will be seen 20 by referring to Fig. 7, the bar is made of two parts or members, one of which has a separable connection with the other. The lower part of the bar is formed from a single sheet of metal and has the central web 25 44, formed by doubling the sheet intermediate its ends, and the outwardly and upwardly extending flanges 45, formed by bending the free ends of the sheet outwardly and upwardly to provide the gutters 30 16'. The other or upper member of the bar is formed by bending a sheet of metal intermediate its end to provide the central open web 46, adapted to have a sliding and embracing fit with the web 44, of the lower 35 member, the free ends of said sheet being bent outwardly and upwardly to provide the glass-plate supporting flanges 47, which carry the glazing strips S, upon which the glass plates rest.

40 In the construction illustrated in Figs. 7 and 8 the cap or crown-piece (not shown) is held in place by means of the bolts 48, each having a head 49, located between the intermediate bends of the upper and lower members 44, and 46 of the bar, the shanks of the bolts passing through openings formed in the ridge of the upper member. The bolts have pointed ends 50, to facilitate the application of the cap or crown as fully set forth 45 herein with reference to the construction 50 illustrated in Figs. 1 and 2.

I do not wish to be understood as limiting myself to the specific details of construction herein shown and described, except as I may be limited by the terms of the appended claims, it being understood that the accompanying drawings are merely illustrative of preferred constructions of my invention. It is to be further understood that I do not 55 claim herein the construction of skylight bar or astragal illustrated in Figs. 7 and 8, as this type of the invention forms the subject matter of a separate application filed by me on the 22nd day of September, 1910, 60 Serial No. 583,209.

What I claim is:

1. In a skylight construction, and in combination with a glass panel thereof, a cushioning member for supporting said panel, said member consisting of a plurality of 70 relatively thin vertical walls of soft metal upon the upper longitudinal edges of which a face of the said panel makes line contact.

2. In a skylight construction, and in combination with a glass panel thereof, a cushioning member for supporting said panel, said member consisting of a channeled strip of soft metal having relatively thin parallel walls upon the upper longitudinal edges of which a face of the panel rests. 75

3. In skylight construction, and in combination with a glass panel thereof, a cushioning member for supporting said panel, said member consisting of a reversible channeled strip of soft metal having pairs of opposed, relatively thin walls upon the upper longitudinal edges of a pair of which walls a surface of the panel rests. 80

4. In a skylight, an astragal having outstanding wings or flanges, cushioning members removably and reversibly supported upon the marginal edges of said wings or flanges, each cushioning member consisting of a channeled strip of soft metal having relatively thin upstanding walls, and glass 95 plates having their under surfaces resting upon the edges of said walls. 90

5. In a skylight, an astragal having outstanding wings or flanges, cushioning members removably and replaceably supported upon the marginal edges of said wings or flanges, each cushioning member consisting of a plurality of relatively thin vertical walls of soft metal, and glass plates resting 100 upon said walls. 105

6. In a skylight, an astragal having outstanding wings or flanges, and cushioning members removably and reversibly supported upon the marginal edges of said wings or flanges, each cushioning member consisting of opposed pairs of relatively thin parallel walls of soft metal, said walls connected intermediate their longitudinal edges by a web. 110

7. In skylight construction, and in combination, a skylight bar, a soft metal cushioning strip removably connected thereto, said strip having a relatively thin upstanding wall constituting the support for a glass plate of the skylight, and means carried by 115 the strip for removably connecting it with the skylight bar. 120

8. In skylight construction, and in combination, a skylight bar, a soft metal glazing strip carried thereby, said strip having a 125 plurality of relatively thin and spaced upstanding walls, and means carried by the strip for removably attaching it to the skylight bar.

9. In skylight construction, and in combi- 130

nation, a skylight bar, and a soft metal cushioning strip removably and replaceably carried thereby, said strip having a channeled portion removably embracing a part of the bar, and a relatively thin upstanding wall, the upper longitudinal edge of which constitutes the support for the glass panel of the skylight.

10. In skylight construction, and in combination, a skylight bar, and a soft metal cushioning strip removably attached thereto, said strip having a channeled portion removably embracing a part of the bar, and a plurality of relatively thin upstanding walls, the upper longitudinal edges of which walls constitute the supporting means for a glass panel of the skylight.

11. In skylight construction, and in combination, a skylight bar, and a soft metal cushioning strip carried thereby, said strip provided with similar means for removably and reversibly attaching the same to the bar and for supporting a glass panel respectively.

25. 12. In skylight construction, a bar comprising a central web, having pairs of upper and lower outstanding wings or flanges on opposite sides thereof, cushioning strips removably carried by and having portions embracing the longitudinal edges of the upper set of wings or flanges, glass plates supported upon said cushioning strips, and a cap or crown piece secured to the said central web of the bar.

35. 13. In skylight construction, an astragal having a central web; glass panels supported by the astragal, rigid bolts projecting upward from the upper edge of the web, said bolts each having a pointed piercing extremity, a cap or crown-piece of thin penetrable metal capable of being pierced by the said pointed extremities of the bolts to form burred openings therethrough the said bolts projecting through said pierced openings 45 in the cap or crown-piece when the latter is in position for use, and a nut screwed upon each bolt, each nut having a countersink to receive the upstanding bur of the opening through which its bolt passes.

50. 14. That improvement in the art of applying caps or crown pieces to skylight constructions, which consists in providing an astragal with rigid cap or crown-piece piercing projections, placing a crown-piece of thin penetrable metal upon the piercing extremities of said projections and forcing the latter therethrough to form burred openings

in said crown-piece through which the said projections extend, and then applying a retaining element to maintain the cap or 60 crown-piece in position.

15. In skylight construction, an astragal having a central web, glass panels supported by said astragal, rigid cap or crown piercing bolts projecting upward from the upper 65 edge of the said web and adapted to pierce burred openings in a cap or crown, and nuts on said bolts, each nut having a countersink on its under face for the purpose specified.

16. In skylight construction, a bar having a web provided with openings along the upper edge thereof, eye-bolts having the headed portions thereof seated in said openings, and means for securing said eye-bolts in said openings and for maintaining the 75 shanks thereof in alinement with the web, said means passing through the eyes of the said bolts.

17. In skylight construction, a bar having a web provided with openings along the upper edge thereof, headed bolts having their heads seated in said openings, and means for securing said bolts in said openings and for maintaining the shanks thereof in alinement with the web, said means 85 passing through the bolt heads and embracing opposite sides of the web.

18. In skylight construction, a bar having a web provided with openings along the upper edge thereof, headed bolts seated in 90 said openings and having their shanks projecting above the upper edge of the web, and means embracing opposite sides of the web and extending through the heads of the bolts for maintaining the shanks thereof in 95 alinement with the web.

19. In skylight construction, a bar having a web provided with openings along the upper edge thereof, eye-bolts seated in said 100 openings and having the shanks thereof projecting above the upper edge of the web, washers embracing opposite sides of the web and the heads of the bolts, and means passing through the washers and eye-bolts for securing the latter in position with their 105 shanks in alinement with the web.

In testimony whereof I have hereunto set my hand in presence of two subscribing witnesses.

JEFFERSON D. THOMPSON.
